UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

FEEDING DEVICE FOR ROCK DRILLS

Application filed February 19, 1929. Serial No. 341,106.

This invention relates to rock drills, but more particularly to a feeding device for rock drills.

The object of this invention is to enable the construction of a feeding device of the pressure fluid operated type whereby a piston in the cylinder placed rearwardly of the rock drill shell may be operated on by pressure fluid at the end having the greater exposed area to cause pressure on that end to retract the drill from the work. By means of this device that side of the piston adjacent the piston rod is acted upon by pressure fluid to cause the rock drill to be moved toward the rock surface being drilled.

The object is attained by the mechanism shown in the accompanying drawings, in which

Figure 1 is a longitudinal elevation of the rock drill shell and feeding cylinder partly in cross section, and

Figure 2 is a vertical cross sectional view of the rock drill and shell taken on the line 2—2 of Figure 1 looking in the direction indicated by the arrows.

Referring more particularly to the drawings, a rock drill 4 is slidably mounted on the guides 6 of a rock drill shell or cradle 8. The shell 8 is of substantially standard construction having the usual conical projection 10 for securing the shell to a quarry bar (not shown) or other supporting means. A cylinder 12 is secured to the rock drill shell 8 by means of bolts 14 and 16 or the cylinder 12 may be integral with the shell 8. A back head 18 forms a closure for the rearward end of the cylinder and a cylinder head 20 having an aperture 22 provides a closure for the forward end of the cylinder 12. A piston 24 slidably mounted in the cylinder 12 has a piston rod 26 attached thereto by means of a reduced portion 28 and a nut 30 screwed onto the threaded end 32 of the reduced portion. Packing means 34 prevents leakage of pressure fluid from the forward end of the cylinder. The piston rod 26 passes through an aperture 36 in the packing means 34 and the protruding end 38 of the piston rod is serrated to form a rack 40.

A rack 42 is formed on the under side of

the rock drill 4 and a pinion 44 rotatably mounted on a shaft 46 which passes transversely through the shell 8 is secured in place by pins 48. Spacers 50 hold the pinion 44 centrally in the shell 8.

A throttle valve casing 52 is secured to the rearward end of the cylinder 12 and a two-way throttle valve 54 operatively connected to a throttle valve handle 56 is mounted therein. Pressure fluid conduits 58 and 60 convey pressure fluid from the throttle valve to the front and rear ends respectively of the cylinder 12 and a pressure fluid supply pipe 62 carries pressure fluid to the throttle valve chamber 55 from a source of supply (not shown).

The operation of the feeding device is as follows: Assuming the rock drill and shell to be in the relative position shown in the drawings and that it is required to withdraw the rock drill from the rock surface being drilled, the operator turns the throttle valve into the position shown in Figure 1. This permits pressure fluid to be exhausted from the front end of the cylinder 12 through the conduit 58 and out of an exhaust port 64 in the throttle valve casing 52. At the same time pressure fluid is admitted to the conduit 60 thence to the rearward end of the cylinder 12. The pressure fluid acts upon the rearward face of the piston 24 forcing it downwardly. The motion of the piston 24 is transmitted through the rack 40 to the pinion 44 which is caused to revolve in a clockwise direction. The pinion 44 acts upon the rack 42 to lift the rock drill 4 away from the rock surface. When it is desired to advance the drill toward the work, the throttle valve 54 is turned so that pressure fluid passes from the conduit 62 into the conduit 58 forcing the piston rearwardly to the position shown in the drawings. At the same time pressure fluid is exhausted from the rearward end of the cylinder 12 through the conduit 60 and out of the exhaust port 64.

It should be noted that the motion imparted to the rock drill is always in the reverse direction to the motion of the piston 24. By means of this device it is possible to apply a greater force for lifting the rock drill than

would be possible if the reversing means described above was not used, for it will readily be seen that the effective area of the piston on the side away from the piston rod is considerably larger than the area on the side from which the piston rod extends. This also makes it possible to use a cylinder of smaller diameter than would be necessary in a device in which the rock drill moved in the same direction as the piston. It also permits of the placing of the feeding cylinder on the rearward end of the rock drill away from the surface of the rock being operated upon and thus the objects hereinbefore mentioned are attained.

I claim:

1. A feeding device for rock drills comprising a rock drill, a rock drill shell, a cylinder mounted in the shell, a piston reciprocably mounted in the cylinder, a piston rod attached to said piston, a rack on the rock drill, a rack on the piston rod, means for selectively admitting pressure fluid to either end of the cylinder to cause the piston to move, and a pinion cooperating with the racks to transmit movement of the piston to the rock drill in the reverse direction.
2. A feeding device for rock drills comprising a rock drill, a rock drill shell, a cylinder mounted on the shell, a piston reciprocably mounted in the cylinder, a piston rod attached to the piston, a rack on the piston rod, a rack on the rock drill, a pinion rotatably mounted on the shell, said pinion cooperating with the rack on the piston rod and with the rack on the rock drill, a pressure fluid distributing valve mounted on the cylinder to selectively admit pressure fluid into either end of the cylinder to cause the piston to move in one direction or the other whereby the rock drill is caused to move in the direction opposite to the movement of the piston through the medium of the racks and the pinion.
3. A feeding device for rock drills, comprising a rock drill and a shell, a feeding cylinder extending rearwardly from the shell, a piston in the cylinder, a piston rod secured to the piston and projecting forwardly from the cylinder towards the rock drill, means for selectively admitting pressure fluid to either end of the cylinder to reciprocate the piston and the piston rod, and rack and pinion means associated with the piston rod and the rock drill adapted upon movement of the piston rod in one direction to cause movement of the rock drill in the opposite direction.

In testimony whereof I have signed this specification.

CHARLES C. HANSEN.
